UNITED STATES PATENT OFFICE.

FRANK HUDSON, OF DOLGEVILLE, CALIFORNIA.

DUMP-CAR.

No. 913,893.

Specification of Letters Patent.

Patented March 2, 1909.

Application filed December 9, 1907. Serial No. 407,420.

To all whom it may concern:

Be it known that I, FRANK HUDSON, a citizen of the United States, residing at Dolgeville, in the county of Los Angeles and State of California, have invented new and useful Improvements in Dump-Cars, of which the following is a specification.

An object of this invention is to so construct a dump car that in the operation of dumping the same by tilting the body of the car, the lower end of a door at that side or end of the car toward which the car body is tilted, will be automatically carried up forwardly away from the level at which it stands when the car-box is upright, thus to leave a large and unobstructed opening through which the contents of the car-box or body can be dumped. That is to say, by this invention the car-floor and the lower end of the door simultaneously recede each from the other during the tilting motion given to the car body.

Strength, simplicity and free action of the parts are also objects in view.

Another object is to hold the door rigidly in whatever position it assumes, and to prevent the same from flapping or swinging loosely at any time.

Another object is to provide positive means for holding the door shut whenever the car is in upright position, and to make it impossible for any opening to occur at the door except when the car is tilted.

Another object is to avoid any pressure or frictional resistance of the load on the door during the operation of dumping.

The accompanying drawings illustrate the invention.

Figure 1 is a side elevation of the dump car with parts in position for carrying a load. Dotted lines indicate the tilted or dumping position. Fig. 2 is a perspective side view of the same car in the act of dumping. Fig. 3 is a perspective view of said car from the same side of the carriage, showing the body of the car tilted to dump sidewise from the carriage. Fig. 4 is a plan of the car.

1 designates the carriage of the car, and 2 a turntable pivoted thereto at 3. These several parts may be of the usual construction.

4 is the car body which may be of any approved form of construction, and is hinged or pivoted to the front end of the turntable, as shown at 5. In the form shown, the car body is a rectangular sheet-metal box, the

floor, two sides, and one end wall of which are fixed rigidly to each other. The top and one end of said box are open.

6 is a door for closing the open end of the box. The same is provided with brackets 7, 8, at the upper and lower ends terminating in pivots 9 and 10 on each side of the door. The turntable 2 of the carriage is provided with a door-support comprising two stationary forwardly-sloping standards 11, 12, supported by struts 13 and projecting upwardly and forwardly from the turntable 2. The upper door pivots 9 are pivoted to the upper ends of said standards.

14 designates two rigid links pivoted respectively to the box or car body walls by pivots 15 at the upper corner thereof, at the closed end of the box, and by the pivots 10 to the lower end of the door 6. The space between the pivots 15 and 10 of the links 14 is approximately equal to the diagonal of the box side from the upper rear corner to the lower front corner.

16 is a brace connecting the upper corners of the side walls at the open end of the box to hold the same in true position.

17 designates springs to resiliently support the closed end of the box when the box is in load-holding position. Said springs may be bent up from the straps 18 that hold the pivot 5 on the turntable.

19 designates the usual spring-pressed latch to engage a keeper 20 when the rear end of the box is down.

21 designates a foot-piece for retracting the spring-pressed latch 19 to release the box.

22 designates the usual handle for tilting the box.

When the box is in the load-carrying position shown in Fig. 1, it rests upon the turntable of the carriage, and the door 6 is held by the links or bars 14 in vertical position in the open end of the box.

Whenever it is desired to dump the load, the closed end of the box may be lifted to tilt the box on its axle or pivot 5. As the box is thus tilted, the open end thereof correspondingly lowers away from the upper door pivots 9, and at the same time the rear pivots 15 move upward and forward, thereby pushing forward and upward the lower end of the door 6 at the same time that the open end of the box moves downward and backward. By this reverse movement of these two parts the opening at the front end of

the box is rapidly widened to allow the load to pass through.

It is to be understood that the invention is not limited to a construction in which the pivot for the box is carried by a turntable, or that the turntable is a part of the invention.

By pivoting the box and the door to relatively stationary supports and connecting the box and the door by link means that tend to swing the door open as the box tilts, the load is practically prevented from frictionally contacting with the door in the act of dumping.

I claim:

- 15 1. A dump car provided with standards, a box open at one end and pivoted to tilt relatively to said standards, a door pivoted to said standards and adapted to close the open end of the box when said box is un-tilted, and links pivoted to the door below its supporting pivots and pivoted to the box, at the upper rear portion thereof.
- 20 2. The combination with a carriage, of a box pivoted thereto, standards on the carriage, a door for the box pivoted to the standards, and means connecting the door and the box to move the door on its pivots as the box moves on its pivot.
- 25 3. A carriage provided with standards, a box pivoted to the carriage and provided with an open end between said standards, a

door pivoted to said standards and arranged in the open end, and links pivoted to the box and to the door to swing said door forward and upward whenever the floor of the box tilts forward and backward.

4. The combination with a carriage, of a box pivoted thereto, a door for the box pivoted to the carriage, and means connecting the box with the door to operate the door as the box moves on its pivot.

5. A carriage provided with a turntable, standards on the turntable, a box pivoted to tilt on the turntable and provided with an open end, a door pivoted to the standards and adapted to close said open end of the box when the box is upright, and rigid link means pivoted to the box and to the door to hold the door closed when the box is upright and to open the door when the box is tilted.

6. A turntable, a box thereon pivoted to tilt, a door for the box pivotally connected with the turntable, and means connecting the door and the box to automatically swing the door as the box tilts.

In testimony whereof, I have hereunto set my hand at Los Angeles, California, this 30th day of November, 1907.

FRANK HUDSON.
